W. C. BOOTS

HOOK

Filed April 7, 1926

Inventor

William C. Boots
By Joseph A. Miller
Attorney

UNITED STATES PATENT OFFICE.

WILLIAM C. BOOTS, OF ATTLEBORO, MASSACHUSETTS, ASSIGNOR TO GUYOT BROTHERS COMPANY, INC., OF ATTLEBORO, MASSACHUSETTS.

HOOK.

Application filed April 7, 1926. Serial No. 100,369.

This invention relates to certain new and useful improvements in hooks and pertains more especially to hooks employed in connection with watch bracelets.

5 The primary object of the invention is to provide a hook which can be easily and quickly released and also engaged by mere movement of the bail bar or loop of the watch, or there part with which the hook 10 engages, thereby eliminating the necessity of operation of the hook to release same, and further separate movement of the bail or bar of the watch or other part, out of engagement with the hook, or into engagement 15 with the latter.

Further the invention aims to provide a hook which is positive in its holding action and in which accidental disengagement of the hook is minimized.

20 Still further, the invention aims to provide a hook of simple and economical construction and capable of easy and quick assembly.

In the drawings:—

25 Figure 1 is a bottom plan view of the invention,

Figure 2 is a section on line 2—2 of Fig. 1,

30 Figure 3 is a section on line 3—3 of Fig. 1,

Figure 4 is a sectional detail perspective view of the guides for the spring.

In proceeding in accordance with the present invention a hook 1 is provided having its shank formed with ears 2. A latch 35 of substantially L-shape is provided and has its sides offset at 4 to form a central raised and hollow guide rib 6. The ears 2 are bent over upon the sides of the latch and are engaged with the sides of the rib 6 so as to permit of free and easy sliding of the latch. The sides of the latch are further formed with curled or rolled guides 5 which engage the back 7 of the hook and the ears 2, thus with the rib 6 affording a 40 three point guide for the latch.

The front end 8 of the latch is extended inwardly and engages the back 7 of the hook and is formed with an offset 9 which

latter affords an abutment to engage the 50 watch bar, not shown.

A coil spring 10 is employed to tension the latch and at one end is received in a U-guide 11 that in turn is held between the back 7 and the hollow interior of rib 6. 55 A presser 12 conforms in shape to the end 8 and offset 9 of the latch and has a shank 13 which is received in the opposite end of the spring 10. The rear end 14 of the rib 6 engages the closed end of the spring guide 11. 60 The rear end of the back 7 may be curled at 15 to provide an eye for attachment to the bracelet end 13.

In operation, it will be noted that the offset 9 forms a seat receiving the free end of 65 the hook and is normally held engaged therewith by the action of the spring 10. To engage a watch bar or other part with the hook, it is merely necessary to effect movement of the bar to engage abutment 9 70 so as to urge the latch against the action of the spring thereby to admit the latch to the hook. To disengage the bar or other part, the same is caused to engage end 8 of the latch so as to move the latter to a 75 position to release the bar or part from the hook.

It will be noted that no solder is required in uniting the parts and that the latter can be easily and quickly connected to the hook 80 shank, by mere bending of the ears 2.

Having thus described my invention what I claim as new and desire to secure by Letters Patent is:—

1. In a device of the type described a 85 hook having a shank provided with side ears, a latch of substantially L-shape having rolled side guides and an offset central hollow rib, the shank ears being engaged over the side guides and slidably engaged with the sides of the rib, one end of the latch having an offset forming a seat to receive the free end of the hook, a spring, a U-guide in the rib for one end of the spring, and a presser engaged with said end of the latch and with its offset and having a stem received in the opposite end of the spring, the rear end of the back of the hook being 90 95

turned inwardly and engaged with the U-guide.

2. In a device of the type described, a hook having a shank provided with side ears, a latch of substantially L-shape having rolled side guides and an offset central hollow rib, the shank ears being engaged over the side guides and slidably engaged with

the sides of the rib, one end of the latch having an offset forming a seat to receive ¹⁰ the free end of the hook, and spring pressed means for the latch.

In testimony whereof I have signed my name to this specification.

WILLIAM C. BOOTS.
